AUTOMATIC LOCK SLIDER

Louis H. Morin, Bronx, N. Y.

Application April 24, 1946, Serial No. 664,585

7 Claims. (Cl. 24—205.14)

1

This invention relates to sliders for separable fastener stringers. More particularly, the invention deals with sliders of what I term the side locking type, wherein the lock element of the slider is movable laterally with respect to the scoops of the stringers and normally held in position between adjacent scoops on a stringer in retaining the slider against movement in either direction thereon. Still more particularly, the invention includes means for automatically moving the lock element of the slider into inoperative position in actuating the pull of the slider to move the slider in either direction on the stringers. The novel features of the invention will best be understood from the following description, when taken together with the accompanying drawing, in which certain embodiments of the invention are disclosed, and in which the separate parts are designated by suitable reference characters in each of the views, and in which:

Fig. 1 is a plan view of a slider made according to my invention, diagrammatically illustrating the same on a pair of stringers with parts of the construction broken away and in section.

Fig. 2 is a section on the line 2—2 of Fig. 1, showing the scoops of one stringer with the lock element therebetween.

Fig. 3 is a section on the line 3—3 of Fig. 1.

Fig. 4 is a section on the line 4—4 of Fig. 3, with parts broken away.

Fig. 5 is a perspective view of the lock element, detached.

Fig. 6 is a plan view showing a modified form of slider construction; and

Fig. 7 is a section on the line 7—7 of Fig. 6, on an enlarged scale.

In sliders of the kind under consideration, it has been the common practice to provide a lock element or pin member movable vertically into position between scoops of the stringers to lock a slider against movement longitudinally of the stringer. Furthermore, this lock element or pin member has formed a part of the pull and in the event that the pull becomes displaced, the slider has been free to move along the stringers, thus failing to perform the desired function.

It is the purpose of my invention to overcome the objectionable features to the present type of lock sliders by providing a lock element which is

independently controlled insofar as movement thereof into locked position is concerned, and which may be moved into an inoperative or non-locking position by exerting a pull upon the fingerpiece of the slider in either of two directions. During the interval when the fingerpiece is being pulled, the slider moves freely along the stringers in response thereto, but otherwise the fingerpiece is free for swinging movement on the slider without contributing any action upon the lock element to release it from locked position. It will also become apparent that in manually moving the slider along the stringers, the instant the pull is released, the lock element will automatically be moved into locked position by the spring employed.

In Figs. 1 to 5 inclusive, I have shown one adaptation of my invention, and in these figures, 10 represents the slider body comprising a top wall 11 and bottom wall 12, these walls being connected by a frog or web 13 at the wide end of the slider in accordance with conventional practice. The walls 11 and 12 have inturned flanges at their inner adjacent faces, as at 14 and 15, note Fig. 3, to define the channel 16 in which the scoops 17—17' of a pair of stringers 18—18', indicated in dot and dash lines in Figs. 1 and 3, are adapted to operate. The scoops are diagrammatically illustrated in Fig. 1 of the drawing and the scoops 17 of the stringer 18 are shown in full lines in Fig. 2 of the drawing in order to illustrate the arrangement of the lock element, later described, between adjacent scoops in retaining the slider against movement on the stringers.

In the construction shown in Figs. 1 to 5 inclusive, the upper wall 11 of the slider has on its outer face, an elongated recess 19 in which is mounted a retaining plate 20 for retaining a slide 21 against displacement from the wall 11 and within a narrower elongated aperture 22. The plate 20 is held in position by a plurality of inwardly turned lugs 23, note Fig. 1 of the drawing.

The slide 21 has substantially centrally of the outer surface thereof an upwardly projecting lug 24, recesses at opposite side surfaces, as indicated at 25 in dotted lines in Fig. 3 of the drawing to receive inwardly extending pivot portions 26 on a pull 27. One end of the slide 21 has on

3

the lower surface thereof a substantially triangular recess 28 defining diverging cam surfaces 29 and 30, note Fig. 4. These camming surfaces intersect in a rounded intermediate portion 31, in which a pin member 32 of a lock element 33 normally seats.

Considering Fig. 3 of the drawing, it will appear that the wall 11 has a transverse recess 34 which is enlarged at its inner end, as seen at 35, in Fig. 4 of the drawing. The element 33 is mounted in this recess to move laterally or transversely with respect to the movement of the slider along the stringer. The pin 32 projects upwardly into the recess 28, and the element 33 includes at its outer end a downwardly projecting lock lug 36 which is adapted to extend into the channel 16 in the normal lock position of the element 33 and to be positioned between adjacent scoops on a stringer, as clearly seen in Fig. 2 of the drawing, and also indicated in Fig. 3. The lug 36 operates in a further cutout portion 37 of the wall 11, which cutout portion also opens through the side edge of the slider wall, so as to permit outward movement of the element 33 including the lug 36, to clear the channel 16, or to permit free movement of the scoops through the channel 16 of the slider. The element 33 carries at its inner end a projecting finger or lug 38, against which one end 39 of a U-shaped spring 40 is adapted to bear to normally retain the element 33 in locked position. The other end 41 of the spring 40 bears against the wall 42 of the aperture 22, the spring 40 being positioned below the slide 21, as will clearly appear from a consideration of Fig. 2 of the drawing.

From the foregoing, it will appear that when the fingerpiece or pull 27 is in normal position, the spring 40 supports the element 33 in normal position, with the lock lug 36 between scoops of a stringer, for example, the scoops 17 of the stringer 18, which position of the parts is shown in Figs. 1, 2 and 3 of the drawing. In grasping the pull 27 to move the slider downwardly to separate the stringers, the slide 21 will move downwardly in the top wall 11, causing the pin 32 to ride over the cam surface 29, which will move the lock element 33 outwardly against the action of the spring 40 or the end 39 thereof, as seen in Fig. 4 of the drawing.

In moving the slider upwardly or in the opposite direction, the slide 21 will move upwardly or in the direction of the wide end of the slider and the pin 32 will move over the cam surface 30, producing the same result, namely moving the lock element 33 outwardly or to the left. All of the above descriptions are applied to the slider, as seen in the drawing. When the pull 27 is released, the slide 21 will be returned to neutral position by action of the spring end 39 upon the finger or lug 38, which moves the element 33 into locked position and seats the pin 32 in the rounded intersection 31 of the recess 28, which position is indicated in Fig. 1 of the drawing.

In Figs. 6 and 7 of the drawing, I have shown a modification, in which the plate 20 is dispensed with and a slide 21', substantially similar to the slide 21 is employed, the slide 21' having bevelled side walls 43 slidably engaging correspondingly formed elongated ribs 44 extending longitudinally of the top wall 11' of a slider.

The slide 21' has the pivot lug 24' similar to the lug 24 and the triangular recess 28' similar to the recess 28. At 33' is shown a lock element substantially similar to the element 33, and having a lock lug 36' at one end, an extension 38' at

4

the other end similar to the extension 38 adapted to engage the end 39' of a spring 40', the spring being bent around a pin portion 45, extending upwardly into the recess 46, which recess terminates at the point 47, shown in Fig. 6 of the drawing. The recess 46 receives the element 33' and thus opens outwardly through the side of the slider wall 11', as at 48. The element 33' carries an upwardly extending pin 32', similar to the pin 32, which operates in the recess 28'.

In Fig. 7 of the drawing, 12' represents the bottom wall equivalent to the wall 12, and at 13' is shown the web joining the slider walls 11'—12' and at 16' is shown the channel of the slider. In Figs. 6 and 7, the lock element 33' is shown in locked position.

With the construction shown in Figs. 6 and 7, it will appear that the slide 21' is exposed at the outer surface of the slider and is movable longitudinally thereof within the channel formed by the ribs 44. However, the operation of the slider shown in these figures will be the same as that of the other figures insofar as actuation of the element 33' is concerned, and therefore, no further detailed description is herein given.

Returning now to Figs. 1 to 5 inclusive, it will appear that the closure plate 20 has an elongated aperture 20' therein in which the pivot lug 24 of the slide operates in movement of the slide longitudinally of the slider.

With the construction shown in Figs. 1 to 4 inclusive, it will be apparent that the lugs 23 are normally open to admit the plate 20 and in the assemblage, the lock element 33 and spring 40 are first placed in position, the element 33 passing downwardly through an opening 11a formed in the wall 11, after which the slide is placed upon said element and spring and then the plate 20 is put into position, after which the lugs 23 are forced inwardly.

Considering Figs. 6 and 7 of the drawing, here the element 33' is first dropped in position through the opening 44' provided in one of the ribs 44. The spring 40' is then placed in position, after which the slide 21' is mounted in the groove with the ribs in an open position, the same as the lugs 23, thereafter, the ribs are bent inwardly to freely engage the bevelled walls 43 of the slide and thus retain the parts in assembled relationship.

It will be understood that the slider body as well as the lock element and the slide can each readily be formed as die castings, and from this standpoint, comprise independent articles of manufacture and assemblage can be made at any time by simply turning in the retaining lugs or ribs. By reason of this construction, a very simple and economical slider structure is produced. As a matter of fact, aside from the U-shaped spring employed, the entire slider device may be composed of any suitable die cast material.

Having fully described my invention, what I claim as new and desire to secure by Letters Patent is:

1. A lock slider for separable fastener stringers, said slider comprising a body having flanged walls joined and spaced at one end by a connecting web, the flanged walls of the slider forming a channel for reception of scoops of separable fastener stringers in coupling and uncoupling the same by movement of the slider longitudinally of the stringers, a lock member mounted in one wall of the slider and movable in its entirety transversely of said wall, said member

having a non-bevelled non-ratcheting lug adapted to project into the channel of the slider between scoops of one stringer in retaining the slider against movement on the stringers, tensile means supporting the lock member in operative position, means comprising a slide member movable longitudinally of said wall of the slider and operatively engaging said lock member to move the same into inoperative position in movement of said slide member in the direction of either end of said slider, said slide member having a shorter length than said wall of the slider and being movable within the end boundaries of said wall, and the operative engagement between said lock and slide members comprising a pin on one of said members operating in a recess in the other of said members, said recess being defined by cam walls.

2. In lock sliders of the class described comprising a channeled slider body defined by spaced walls joined by a connecting web at one end thereof, the combination therewith of a lock element in one of said walls, said lock element being movable as a unit transversely of said wall and having a non-bevelled non-ratcheting locking finger adapted to extend into one of said slider channels, a spring operable on said lock element to urge the latter in one direction, a longitudinal member overlying said spring and lock element, said longitudinal member being movable relatively to said wall, and interengaging means on the longitudinal member and the lock element whereby movement of the longitudinal member serves to move the lock element against the action of the spring.

3. In lock sliders of the class described comprising a channeled slider body defined by spaced walls joined by a connecting web at one end thereof, the combination therewith of a longitudinal recess in one of said walls, a transverse recess in said wall intersecting the longitudinal recess and extending to a lateral edge of said wall, a lock element in the transverse recess which is movable as a unit therein, said lock element having a non-ratcheting locking finger adapted to extend into one of said slider channels, a spring in the longitudinal recess operable on the lock element to urge the latter in one direction in the transverse recess, a flat movable member in the longitudinal recess overlying said spring and the lock element, and interengaging means on said member and the lock element whereby movement of the member serves to move the lock element against the action of the spring.

4. In lock sliders of the class described comprising a channeled slider body defined by spaced walls joined by a connecting web at one end thereof, the combination therewith of a longitudinal recess in one of said walls and a transverse recess in said wall intersecting the longitudinal recess, a lock element in the transverse recess movable in its entirety therein, said lock element having a non-ratcheting lock finger extending into one of said slider channels, a spring in the longitudinal recess operable on said lock element to urge the latter in one direction in the transverse recess, a longitudinal member in the longitudinal recess overlying said spring and lock element, said longitudinal member being movable in said longitudinal recess, interengaging means on the longitudinal member and the lock element whereby movement of the longitudinal member serves to move the lock element against the action of the spring, a pull

coupling member on said longitudinal member adapted to extend above said slider wall, and a pull attached to said pull coupling member and adapted to extend loosely over either end of the slider.

5. In lock sliders of the class described comprising a channeled slider body defined by spaced walls joined by a connecting web at one end thereof, the combination therewith of a longitudinal recess in one of said walls and a transverse recess in said wall intersecting the longitudinal recess, a lock member in the transverse recess having a non-ratcheting lock finger extending into one of said slider channels, said lock member being movable in its entirety in the transverse recess, a spring in the longitudinal recess operable on said lock member to urge the latter in one direction in the transverse recess, a movable member in the longitudinal recess, and interengaging means on the movable member and the lock member whereby longitudinal movement of the movable member serves to move the lock member against the action of the spring, said interengaging means comprising an opening in one of said members defined by cam walls and a projection on the other of said members engageable with said cam walls.

6. In lock sliders of the class described comprising a channeled slider body defined by spaced walls joined by a connecting web at one end thereof, the combination therewith of two longitudinal recesses in one of said walls, one of said recesses being disposed above and opening into the other, a transverse recess intersecting the second longitudinal recess and opening through a lateral edge of the slider wall, a lock element in the transverse recess extending to said lateral edge of the slider wall, said lock element being movable in its entirety in the transverse recess and having a non-ratcheting locking finger adapted to extend into one of said slider channels, a spring in the second longitudinal recess operable on the lock element to urge the latter in one direction in the transverse recess, an elongated member in said second longitudinal recess overlying the spring and the lock element, said member being movable in the second longitudinal recess, interengaging means on the member and the lock element whereby movement of the member serves to move the lock element against the action of the spring, a plate in the first longitudinal recess overlying said member, an elongated aperture in said plate, a pull coupling member on said elongated member extending through said aperture and projecting above said slider wall, and having a non-bevelled non-ratcheting locking finger adapted to extend into one of said slider channels.

7. In lock sliders of the class described comprising a channeled slider body defined by spaced walls joined by a connecting web at one end thereof, the combination therewith of two longitudinal recesses in one of said walls, one of said recesses being disposed above and opening into the other, a transverse recess intersecting the second longitudinal recess, a movable lock element in the transverse recess having a non-ratcheting lock finger extending into one of said slider channels, a spring in the second longitudinal recess operable on the lock element to urge the latter in one direction in the transverse recess, a movable member in said second longitudinal recess overlying the spring and the lock element, interengaging means on said member

and the lock element whereby movement of the member serves to move the lock element against the action of the spring, and a stationary member in the first longitudinal recess overlying the movable member.
